FERDINAND E. ENGLISH, OF ST. LOUIS, MISSOURI.

BANDEAU FOR HATS AND THE LIKE.

1,157,093.

Specification of Letters Patent. Patented Oct. 19, 1915.

Application filed April 12, 1915. Serial No. 20,768.

To all whom it may concern:

Be it known that I, FERDINAND E. ENGLISH, a citizen of the United States, residing at the city of St. Louis, State of Missouri, have invented a certain new and useful Bandeau for Hats and the like, of which the following is a specification, reference being had to the accompanying drawing, forming a part thereof.

This invention relates to a certain new and useful bandeau for hats and the like, the principal object of my present invention being to provide a bandeau of simple form and inexpensive manufacture which, while especially adapted and designed for use in connection with so-called soft hats as distinguished from so-called stiff hats, may be readily, easily, and conveniently attached to, and secured within, a hat, either soft or stiff and of a certain fixed or predetermined head-size, for not only adjustably reducing the predetermined size of the head-opening to adapt the hat to comfortably and yieldingly interchangeably fit, within certain limits, heads of various sizes, but also serving as a yielding retaining means for the hat upon the head.

With the above and other objects in view, my present invention resides in certain novel features of form, manufacture, construction, arrangement, and combination of parts, all as will hereinafter be described and afterward pointed out in the claims.

In the accompanying drawing, which illustrates my new bandeau in preferred form, Figure 1 is a perspective view of a so-called soft hat provided or equipped with a bandeau embodying my invention; Fig. 2 is an enlarged detail and fragmentary view showing in section the bandeau and hat operatively secured together; Figs. 3 and 4 are enlarged fragmentary views of the bandeau in course of manufacture; Fig. 5 is a cross sectional view of the bandeau in course of manufacture on approximately the line 5—5, Fig. 3; and Fig. 6 is an enlarged fragmentary view of the finished bandeau, showing the means preferably employed by me for securing or fastening the bandeau in approximately ring or elliptical shape ready to be inserted into and engaged with a hat.

Referring to the said drawing, in which like reference characters refer to like parts throughout the several views, A indicates a preferably so-called soft hat or the like, which may be of any ordinary or preferred

form or design and material. This hat A, as shown, comprises a brim 1, a crown 2, and a head-opening 3, or, as I will call it, head-portion 3, which is generally when fully extended to be placed upon the head somewhat elliptical in outline in inverted plan view, is, in the trade, commonly known and designated as the head-size of the hat, being that part of the hat which is designed to fit the head. Brim 1, crown 2, and head-portion 3 are herein shown as integrally forming hat A, but it will be obvious and readily understood that said parts may be separate members fixed or secured together in any suitable manner to form the hat proper.

B indicates my new bandeau. This bandeau B is made of specially manufactured material comprising integrally a plurality of fabric woof threads 4 interwoven preferably on the bias across and between a plurality of elastic warp strands 5 preferably of rubber or analogous material and a non-elastic warp strand 6 preferably of spring steel cylindrical in form, all as clearly seen in Figs. 3, 4, and 5. The method of manufacturing my new bandeau material is practically similar to the method commonly employed at present in manufacturing elastic webbing. In its manufacture, warp strands 5 and 6 are arranged lengthwise parallel with, and slightly spaced apart from, one another on the same plane with wire strand 6 outermost at one, which I will call the outer, side of the series of strands 5, the width of the finished material being determined and regulated by the number of elastic strands 5 so arranged, as will be understood. Elastic warp strands 5 being now lengthwise elongated and suitably held under tension in abnormal or stretched condition, woof threads 4 are more or less tightly or closely interwoven as described with both elastic strands 5 and non-elastic or wire outermost strand 6, the bandeau material being so manufactured in what might be described as ribbon form of any desired length. The woof threads 4 and warp strands 5 and 6 being so interwoven, and elongating tension on elastic strands 5 being afterward released or removed, strands 5, under their inherent internal fiber or elastic stress, will tend to lengthwise return to normal or unstretched condition, as occurs with ordinary common elastic webbing. Wire strand 6, however, being lengthwise stiff and unyield-

ing, and with which strand woof threads 4 are also more or less tightly interwoven, will resist and retard the elastic lengthwise return of elastic strands 5 to normal unstretched condition. Consequently, warp strand 6 being laterally yielding and the combined elastic pull of strands 5 to return to normal unstretched condition being sufficient to overcome the lateral stiffness or rigidity, as I may call it, of wire strand 6, strands 5 will exert a bending stress or pull on wire strand 6, the finished material being thus automatically, as it might be said, gently bent around, as illustrated in Fig. 4, with elastic strands 5 then in graduated stretched to unstretched condition as they lie innermost from wire or outermost strand 6.

The bandeau material, if manufactured in long so-called ribbon or strip form or if otherwise necessary, is now crosswise cut into proper lengths to fit the particular head-size or portion 3 of the hat A with which they are to be operatively used, and when so cut the same may be easily bent around into approximately ring or elliptical form to fit within the hat, the meeting ends of the cut portion being secured together in any desired or suitable manner, as, for instance, by means of a sheet metal clamp 7 suitably clinched thereupon and particularly into engagement with wire strand 6 thereof, as illustrated in Fig. 6.

The bandeau B in finished approximately ring or elliptical form is now ready to be inserted into the hat A, and in its finished form it will be evident that the wire outermost strand 6 thereof imparts to the bandeau sufficient stiffness or rigidity to take or resist the graduated inward pull of the elastic strands 5, and that, while the elastic strands 5 adjacent wire strand 6 are in relatively stretched condition, the inner strands 5 are in relatively unstretched condition, the bandeau at its internal periphery being consequently elastically free to give or yield laterally relatively to the flat plane thereof.

In use or operation, the bandeau B is suitably, as by means of small sharpened staples or the like 8 engaging wire strand 6 and having their legs projecting through and clinched upon the hat, as illustrated in Fig. 2, attached within head-portion 3 of the hat A preferably at or closely adjacent its lower or outer edge, as seen in Figs. 1 and 2, or, as it might be said, at or adjacent the rim or mouth thereof. Being so attached and secured, and extending continuously around, within the hat, the bandeau is normally, due to its described construction, disposed flatwise throughout its width at an angle inwardly relatively to the head-portion 3 of the hat, or, as it might be described, is normally flatwise disposed approximately horizontally within the area of the opening of

the head-portion 3 of the hat, as clearly seen in Figs. 1 and 2, bandeau B thereby yieldingly reducing the predetermined size—interior area—of head-portion 3 and adjustably adapting the same to fit heads of other sizes. On the hat being placed upon a head having a size smaller than, or even substantially the same as, the predetermined size of head-portion 3 of the hat, but larger than the somewhat elliptical opening into the hat now provided by bandeau B when in its said normal position, bandeau B will yieldingly give inwardly or upwardly at its relatively unstretched inner portion to accommodate the said head. At the same time, bandeau B will yieldingly engage the head without unduly binding thereupon and serve not only as a soft elastic cushion, so to speak, for the hat upon the head, but also as a retaining or securing member therefor. The hat provided with my new bandeau B is thus yieldingly self-securing upon the head, the use of pins or the like for such purpose, in the case of women's and girls' hats, being obviated.

From the foregoing, it will hence be seen that a so-called soft or stiff hat provided or equipped with my new bandeau is readily capable of interchangeably neatly and comfortably fitting heads of various sizes within certain limits depending upon the predetermined size of the head-portion of the hat and the width and elasticity of the bandeau.

I am aware that minor changes in the form, construction, arrangement, and combination of the several parts of my new bandeau may be made and substituted for those herein shown and described without departing from the nature and principle of my invention.

Having thus described my invention, what I claim and desire to secure by Letters Patent is:

1. An approximately ring-shaped bandeau for hats and the like, the same having a body-portion comprising an outermost non-elastic, but laterally resilient warp strand, an inner elastic warp strand normally approximately concentric with said outermost strand, and a plurality of fabric woof threads.

2. An approximately ring-shaped bandeau for hats and the like, the same having a body-portion comprising an outermost non-elastic, but laterally resilient warp strand, a plurality of inner elastic warp strands normally approximately concentric with one another and with said outermost strand, and a plurality of fabric woof threads.

3. An approximately ring-shaped bandeau for hats and the like, the same having a body-portion comprising an outermost non-elastic, but laterally resilient warp strand, a plurality of inner elastic warp

strands normally approximately concentric with one another and with said outermost strand, and a plurality of fabric woof threads, said elastic warp strands being in graduated stretched to relatively unstretched condition as they lie innermost from said outermost strand.

4. An approximately ring-shaped bandeau for hats and the like, the same having
10 a woven body-portion integrally comprising an outermost laterally resilient spring-steel warp strand, a plurality of inner elastic warp strands normally approximately concentric with one another and with said outermost strand, and a plurality of fabric woof threads, said elastic warp strands being in graduated stretched to relatively unstretched condition as they lie innermost from said outermost strand.
- 15 5. An approximately ring-shaped ban-

deau for hats and the like, the same having a woven body-portion integrally comprising an outermost laterally resilient spring-steel warp strand, a plurality of inner elastic warp strands normally approximately concentric with one another and with said outermost strand, and a plurality of fabric woof threads, said elastic warp strands being in graduated stretched to relatively unstretched condition as they lie innermost 25 from said outermost strand, and means for securing the bandeau in approximately ring-shaped form.

In testimony whereof, I have signed my name to this specification, in the presence of 30 two subscribing witnesses.

FERDINAND E. ENGLISH.
